WEATHER STRIP CONSTRUCTION

Forrest F. Beil, Clinton, Iowa, assignor to Curtis
Companies Incorporated, Clinton, Iowa, a cor-
poration of Iowa

Application September 22, 1941, Serial No. 411,867

1 Claim. (Cl. 20—52.4)

My invention relates to a weather sealing construction for the common double hung window.

An object of my invention is to provide a weather sealing construction for a window which will be equally weather-tight for various degrees of shrink and swell of the different parts of the window.

A further object is to provide a weather strip construction which will give a tight seal even though the window is made with such ample mechanical clearance between the sash stiles and the jamb as to avoid sticking under maximum humidity conditions.

Another object is to provide a weather strip which will overcome any tendency of the window to rattle when made with mechanical clearances as referred to above.

Another object is to provide a weather strip which shall engage the sash with a substantially uniform amount of friction per unit length, this friction being variable in a minimum degree with changes in atmospheric conditions.

Still another object is to provide a weather strip construction which can be readily and economically manufactured of wood or similar non-metallic materials.

With these and other objects in view, my invention consists in the construction, arrangement and combination of the various parts of my weatherproof window construction whereby the objects contemplated are attained, as herein-after more fully set forth, pointed out in my claim, and illustrated in the accompanying drawing, in which:

Figure 1 is a perspective sectional view of a fragmentary portion of a window embodying my construction;

Figure 2 is a horizontal cross sectional view through such a window; and

Figure 3 is an enlarged perspective view of the weather strip member.

The disadvantages of the ordinary type double hung window are well known. If made with small enough clearance so that it does not leak excessively in cold dry weather, it gives trouble due to sticking of the sash in relatively humid weather. An important function of a weather seal construction, therefore, is to give a good seal throughout the range of shrinking and swelling which may be experienced by the wood parts of the window.

In the common type of window, if there is clearance enough for easy operation, a little wind or vibration of the building will cause the sash to rattle annoyingly. Hence it is desirable that

the weather seal prevent rattling of the sash, whether shrunken or swollen.

If the builder desires to avoid the disadvantages of pulley-and-weight suspension by using springs, then it is important to have the friction between sash and jamb uniform, controllable, and subject to minimum variation with changing atmospheric conditions.

In the accompanying drawing I have used the reference numeral 10 to indicate a side jamb of a window frame. The numeral 12 indicates generally the upper sash, and the numeral 14 indicates generally the lower sash.

In Figure 1 may be seen a stile 16 and a meeting or check rail 18 of the upper sash 12, and a stile 20 and the check rail 22 of the lower sash 14.

Fitted in a groove in the side jamb 10 is the customary parting stop 24. Where spring suspension is desired, the sash members may be formed with grooves 26, and the jamb with corresponding grooves 28 to receive the springs 30.

Grooves 32 are formed in the vertical edges of the sash 12 and 14, and corresponding grooves 34 are formed in the side jamb.

For making a weather-tight, easy-sliding joint I provide a weather strip member 35 which is shown particularly in Figure 3. This strip can be made of wood or other similar material, and is conveniently formed from a piece having rectangular cross section. One edge of such a piece is left in rectangular form, and constitutes the base of the strip, which fits snugly into the groove 34 of the jamb. The part of the strip which extends out of the groove 34 I may refer to for convenience as the projecting portion, and the edge or end surface of this portion as the projecting edge.

The projecting edge of the strip and the side portions adjacent that edge are formed in a manner particularly adaptable for carrying out the objects of my invention. In the sides, two longitudinally extending concave grooves 36 are formed. The shape of these grooves is such that the thickness of the strip at all portions which project out of the groove 34 is substantially reduced, except along two convex surfaces adjacent the formed edge of the strip. These two surfaces, indicated at 38 and 40 in Figure 1, fit against the sides of the groove 32 in the sash, giving not one but two seals against the passage of cold air and dirt between the sash and jamb.

In the projecting edge of the strip I cut a saw kerf 42 which extends into the strip well toward the deepest portion of the grooves 36. The effect of the saw kerf, of course, is to give a degree of flexibility to the engaging surfaces of the

strip, so that when they contact the sides of the groove 32 along the lines 38 and 40 the amount of friction will not vary greatly with shrinking and swelling of the wood. A saw kerf 44 may be made at the bottom of the groove 32, giving a somewhat similar action, although to a much smaller extent, in view of the thickness of the sash stile.

It should be noted that the weather strip guides the movement of the sash, so that the latter can be placed in the frame with adequate mechanical clearance, as indicated, for example, at 46, so that there is no occasion for frictional engagement by the sash with the frame at other places than along the weather strip.

It will be also noted that with the weather strip made as above described, the rubbing surfaces are limited in extent, consisting of the relatively narrow line on each side of the weather strip. The area in frictional contact will not vary substantially with changes in temperature and humidity. The swelling of the wood takes place almost entirely in a direction across the grain rather than lengthwise of the wood. Hence there is an advantage in the fact that the groove 32 is relatively narrow, since the expansion which takes place across the width of this groove will be a relatively small part of the expansion or contraction in the total thickness of the sash.

Any expansion or contraction which does take place across the grain of the sash stiles will be substantially matched by expansion or shrinkage taking place across the grain of the weather strip itself when the latter is made of similar wood, so that the frictional pressure will remain practically constant.

The feature of ability to retain uniform value of friction is important where spring suspension is used, inasmuch as a spring is usually selected which will balance the sash midway of its travel. The weather strips must provide sufficient friction so that the window will stay in position at either extreme of its movement, but of course

excessive friction unnecessarily increases the difficulty of raising or lowering the window. It will thus be appreciated that I have provided a structure which is advantageous in that it will maintain a closely uniform degree of friction, and of course, this amount of friction can be established in manufacture by controlling the distance between the surfaces 38 and 40 of the strip 35, relative to the width of the groove 32, and also by controlling the depth of the saw kerf 42, to just the correct amount for holding the window in place at its extremes of movement.

Although I have shown the weather strip member as fixed in the jamb, it will be apparent that it may be reversed, so that the weather strip is mounted in the sash and slides in the groove in the jamb, in which case the results obtained would be substantially the same as I have above described.

Some other changes may be made in the details of the construction and in the arrangement of the parts of my invention without departing from the real spirit and purpose thereof, and it is my intention to cover by my claim any modified forms of structure or use of mechanical equivalents, which may be reasonably included within their scope.

I claim as my invention:

The combination of a frame having vertical opposite grooves, and a sash slidable in the frame, having similar registering grooves, the sash having at the bottoms of said grooves vertical saw kerfs, with sealing strips having portions of substantially rectangular cross section snugly received in the first grooves and portions slidably received in the second described grooves, to frictionally engage the sides thereof, said last named portions having deep, vertically elongated slots opposite said saw kerfs and having channels in their sides, whereby the parts on opposite sides of the slots have some flexibility.

FORREST F. BEIL.
